UNITED STATES PATENT OFFICE

RAYMOND R. RUNDELL, OF WATERBURY, CONNECTICUT

COMBINED CORKSCREW AND BOTTLE DECAPPER

Application filed July 23, 1930. Serial No. 470,110.

This invention relates to an improvement in combined corkscrews and bottle de-cappers, and particularly to devices for this purpose which are mounted upon the wall or other support and such as are commonly found in hotel rooms, but equally applicable for use in other places. It is common to pivotally mount a corkscrew in a support and in some cases, the corkscrew has been protected so as to avoid the possibility of catching the clothing upon it.

The object of this invention is to provide a corkscrew with a guard, and also to form the guard with a bottle de-capping opening, and the invention consists in the construction as hereinafter described and particularly recited in the claims.

In the accompanying drawings:

Fig. 1 is a face view of a combined corkscrew and bottle de-capper constructed in accordance with my invention;

Fig. 2 is a longitudinal sectional view of the same;

Fig. 3 is a face view showing one modification of my invention;

Fig. 4 is a longitudinal sectional view of the same;

Fig. 5 is a perspective view of a second modified form of my invention;

Fig. 6 is a face view of the plate and corkscrew with the corkscrew cover and bottle de-capper removed;

Fig. 7 is an edge view of the same;

Fig. 8 is a front view of a third modified form of my invention; and

Fig. 9 is a side view of the same.

In the preferred construction of my device, as shown in Figs. 1 and 2 of the drawings, I employ a base 10 with an outwardly-projecting post 11, the base being adapted to be secured to a wall or other support in any desired manner.

Formed integral with the base is a stud 12 vertically slotted to receive the end of a corkscrew 13 which is mounted in the stud by a rivet 14. The under side of the post is formed with a slot 15 to receive the upper end 16 of a sheet-metal guard 17, this guard being secured to the post by a drive-screw 18.

The lower end of the guard is doubled upon itself and extends back of the base 10 which is notched to receive it. The front of the guard is formed with a long vertical slot 19 in line with the corkscrew 13 and through which the corkscrew may be projected. Above the slot 19 is a transverse opening 20 forming a bottle de-capper.

In some cases the base is secured to the wall by providing a plate 21 with a forwardly-projecting arm 22 which extends into the post 11, which is recessed to receive it, and the case is secured to the arm by means of a screw 23 formed at its outer end with a transverse tooth 24 by which it may be turned into place by a suitable tool.

Instead of fixing the guard and de-capper with respect to the post, this guard may be hinged to the post, as shown in Figs. 3 and 4 of the drawings, in which case a box-like guard 25 is pivoted to the post 11, and at the bottom of the guard is a transverse opening 26 forming a de-capping device.

Or, instead of forming the base with a post, the base may be made from sheet-metal in the form of a plate 27 having ears 28 struck from the plate to provide bearings for the upper end of a sheet-metal guard 29. The plate will also be formed with ears 30 between which a corkscrew 31 is pivotally mounted. In this case, the guard is formed with an outwardly-bowed central section 32 to house the corkscrew, and the plate will also be formed with short lugs 33 with which the lower end 34 of the guard may be engaged. This guard is also formed near its upper end with a transverse opening 42 to provide means for de-capping a bottle.

Or, instead of forming the guard separate from the back-plate, it may be formed integral therewith, as shown in Figs. 8 and 9 of the drawings, which show a back-plate 35 formed with lugs 36, between which the corkscrew 37 is mounted, the upper end of the plate bent outward, thence inward and downward, and formed at its lower end with lugs 38 which extend through openings 39 in the back-plate, by which this lower end is fixed to the back-plate. This front is formed with a vertically-arranged clearance-slot 40.

through which the corkscrew may be projected and near its upper end with a transverse slot 41, providing means for de-capping a bottle.

I thus provide, in a simple way, a pivotally-mounted corkscrew with a guard covering the screw in its retired position so as to avoid the possibility of catching the garments of a wearer, a towel or other device, and which guard also provides a bottle de-capper.

I claim:

1. In a bottle-opening device, a base adapted to be attached to a wall, a corkscrew pivoted to said base, and a guard plate mounted in front of said corkscrew for preventing clothing from catching on said corkscrew, said guard plate having a bottle de-capping slot formed therein.
2. A combined corkscrew and bottle de-capper comprising a base, a corkscrew pivotally mounted thereon, a post projecting forward from the base, a sheet-metal guard connected with said post and extending downward below the lower end of the corkscrew, said guard formed with a clearance-slot for the corkscrew and also formed with a bottle de-capping opening.
3. In a bottle-opening device, a base adapted to be attached to a wall, a corkscrew pivoted to said base, and a guard plate pivotally mounted in front of said corkscrew for preventing clothing from catching on said corkscrew, said guard plate having a bottle de-capping slot formed therein.
4. A combined corkscrew and bottle de-capper comprising a sheet-metal base having two pairs of lugs struck outwardly therefrom, a corkscrew mounted between one pair of said lugs and a guard pivotally mounted between the other pair, said guard extending downward so as to cover the corkscrew and formed with a transverse de-capper opening.
5. In a bottle-opening device, a sheet metal base adapted to be attached to a wall, a corkscrew pivoted to said base, and a guard plate adapted to cover said corkscrew and prevent clothing from catching thereon, said guard plate being pivoted to said base and having a sheath-like raised channel to permit said plate to lie in flat contact with said base.
6. In a bottle-opening device, a base adapted to be attached to a wall, a corkscrew pivoted to said base, and a guard plate mounted in front of said corkscrew for preventing clothing from catching on said corkscrew.

In testimony whereof, I have signed this specification.

RAYMOND R. RUNDELL
